MINE TIMBER SETTING LIFT

**Kenneth L. Cook, Paul L. Jarvis, and Woolson H. Davis,
Uhrichsville, Ohio, assignors to Ruger Equipment, Inc.,
Uhrichsville, Ohio, a corporation of Ohio**

Application February 26, 1953, Serial No. 338,978

8 Claims. (Cl. 214—149)

Our invention relates to a mine timber lift. It has to do, more particularly, with a lifting unit for use on a mine car, or other suitable mobile carriage or vehicle, for handling timbers, particularly the timbers used for originally supporting the roof of the mine and for lifting them into place against the roof and holding them in such place until they are shored up in place. Obviously, the device is also useful in removing and replacing the timbers, as well as pulling timber stumps in the mine and in the preliminary handling of the timbers preparatory to final positioning.

Various lift devices have been provided in the past. They are usually very complicated and expensive. Furthermore, they have other disadvantages. For example, they are so designed that in holding the timbers against the roof they may apply excessive pressure thereto which, in itself, would cause loosening of material and caving of the roof. Also, the timber-engaging heads on these prior art lifts have not been such as to obtain maximum efficiency in handling the timbers.

It is the object of our invention to provide a simple and inexpensive lift device which can handle and set the mine timbers efficiently and accurately and which is so designed as to preclude the application of excessive forces to the mine roof.

The lift of this invention is preferably, though not necessarily, of the hydraulic type, and includes oil-powered lift means which is non-explosive so that it can be used with safety in a mine.

The preferred embodiment of our invention is illustrated in the accompanying drawings wherein similar characters of reference designate corresponding parts and wherein:

Figure 1 is a side elevational view of the timber lift of our invention supported on a mine car.

Figure 2 is a plan view of a mine car or mine vehicle showing wells at diagonally opposed corners for receiving the vertical mast of our timber lift.

Figure 3 is a side elevational view of the timber lift removed from the car or vehicle.

Figure 4 is a perspective view of the timber handling head of the lift.

Figure 5 is a diagrammatic view of the hydraulic system of the lift.

Figure 6 is a detail in section of the control valve and pressure-relief valve of the hydraulic system.

Figure 7 is a detail in vertical section of the socket and associated means for receiving and supporting the lower end of the mast.

Figure 8 is a side elevational view showing the timber lift supporting a timber against the roof of the mine.

Figure 9 is a diagrammatic view showing how the lift can be used in handling timbers on an adjacent car or vehicle.

Figure 10 is a side view of a timber-supporting bracket that may be used on the adjacent car or vehicle.

In the drawings we have illustrated our lift device generally by the numeral 10. It is removably mounted on a mine car or vehicle of the usual type which is indicated by the numeral 11 in Figures 1 and 2. The mine car is preferably provided with wells 12 (Figure 2) at diagonally opposed points for receiving the lower end of the vertical mast 13 of our lift. The wells 12 are disposed in openings in the car floor 14 and extend downwardly therethrough but preferably do not extend to a level below the axles 15 of the car wheels. The mast 13 is inserted from above the car floor 14 in a well 12 and is rotatable

2

therein until the handles 16 are used to apply a brake, as will later appear, to nonrotatably clamp the mast in the socket.

The mast 13 may be suitably formed, for example, of telescoping tubular sections which are welded together. To the upper end of the mast 13 a cantilever boom arm 17 has its inner end pivoted at the fulcrum point 18 so that the arm can swing in a vertical plane. Angularly disposed between the arm 17 and the mast 13 is a fluid ram 19 provided for swinging the arm 17 vertically. This ram includes the cylinder 20 pivoted to the lower end of the mast 13 at 21 and the piston and rod 22 which has its upper end pivoted to the arm 17 at a point 23 spaced outwardly from the fulcrum 18.

The outer end of the boom arm 17 carries a timber engaging head 24. This head 24 is in the form of a cradle or yoke 25 which receives and supports a timber.

The cradle 25 (Figure 4) is mounted for rotation through 360 degrees on the upper end of a bifurcated link 26. This link 26, along with a longitudinal bar 27 and with the arm 17 and the upper portion of the mast 13, form parallel linkage for keeping the cradle 25 upright, regardless of the vertical position of the arm 17.

The link 26 is pivoted below its upper end to the arm 17 at a point 28 spaced slightly from the outer end of such arm. The bar 27 has its inner end pivoted to the mast 13 at 29 slightly below its upper end and its outer end is adjustably pivotally connected to the lower end of the link 26. It will be noted from Figure 4 that the outer end of the arm 17 extends through the bifurcated link 26 and the lower end of this bifurcated link has a block 30 (Figure 3) pivoted therein for swinging movement in a vertical plane. The bar 27 is provided on its outer end with a threaded rod portion which extends loosely forwardly through an opening in the block 30 and which carries two adjusting nuts 31 on its outer end ahead of and behind the block. Obviously, the nuts 31 can be used to initially adjust the link 26 into vertical position.

The extreme outer end of the arm 17 is also bifurcated and has a block 32 (Figure 4) pivoted therein for swinging movement in a vertical plane. This block 32 receives the vertical stem of a clevis 33 which carries a hook 34 that is pivoted for swinging in a vertical plane.

The ram 19, preferably a hydraulic ram, is actuated by means of a double-acting hand-pump 35 which is carried by the lower portion of the mast 13. The hydraulic tubing between the ram 19 and the pump includes flexible sections to permit the necessary vertical swinging movement of the ram relative to the mast. The hydraulic system is shown diagrammatically in Figure 5 and includes the pressure line 36 which runs from the pump 35 to the lower end of the cylinder 20. This pressure line 36 has connected to it a line in which a control and pressure-release valve 37 is connected. This valve 37 may be of the type shown in Figure 6 or of any other suitable type. It includes a control knob 38 by means of which it may be actuated manually to control lowering of the boom arm 17. The valve 37 is preferably supported on the mast 13.

The valve of Figure 6 includes a housing 40 which has a pressure inlet passage 41 connected to the pressure line 36 (Figure 5) and an exhaust or drain outlet passage 42 which is connected to the exhaust line 43 (Figure 5) that drains into the sump 44. The inlet passage 41 is formed coaxially with a bore 45 extending through the housing 40 and which has a needle valve 46 disposed therein. The point of this needle is associated with a reduced neck 47 of the bore 45 and the body of this needle is threaded at 48 into the end of the housing. By rotating the knob 38 on the needle, the point thereof can be seated or unseated from the inner end of the neck portion 47. It will be apparent that the inlet passage 41 is at one side of this neck portion 47 and the exhaust passage 42 is at the other side of this neck portion so that the point of the needle will control communication therebetween. The inlet passage 45 has a pressure-release passage 49 leading therefrom to a pressure-release valve 50 mounted on the housing 40. This pressure-release valve has a ball 51 normally seated on the outer end of passage 49 by means of a spring 52. The resistance to unseating of the valve, or in other words the pressure at which the relief valve 50 functions, can be varied by adjustment of the nut 53 threaded into the

outer end of the housing of the valve 50. When the pressure in the inlet passage 45 and the pressure line 36 reaches a maximum for which the valve 50 is set, the ball 51 will be unseated.

As shown in Figure 8, the arm 17 is swung upwardly to lift the timber T in position against the mine roof. The timber T will be cradled in the cradle 25, the prongs of the cradle terminating well below the upper surface of the supported timber so they will not contact the mine roof. The arm 17 will be moved to this position by actuating ram 19 by pumping hand pump 35. The timber T will be pressed against the mine roof with sufficient pressure until it is shored in place. However, excessive pressure, tending to cave the roof, cannot be applied because of the setting of the spring 52 of the relief or overload valve 50. When the pressure in the hydraulic system becomes great enough to overcome the resistance of the spring 52 in the by-pass or pressure relief valve 50, the ball check 51 is forced away from its seat, allowing the oil to by-pass through an orifice 49a to the other side of the neck 47 and thereby to the low pressure side of the hydraulic system, the orifice 49a being connected thereto by a suitable line if desired. The load at the end of the cantilever arm 17 will lower slightly, upon unseating of the ball check 51, but will stabilize at the point that the resistance of the spring 52, in the pressure overload valve 50, overcomes the pressure in the hydraulic system. At this point, the ball check 51 is reseated cutting off the flow of fluid from the high pressure side to the low pressure side of the system. When the arm 17 is extended upwardly as shown in Figure 8, the cradle 25 can be rotated to any desired position through 360 degrees without interference with the arm. When it is desired to lower arm 17, the knob 38 is turned to unseat the needle valve and connect inlet passage 45 to outlet passage 42. By adjusting the needle, the operator can definitely control the lowering speed of the boom arm 17.

In Figure 7 I have illustrated the structure of each well 12 and the associated bearing structure for the mast 13. This well structure will receive the mast 13 from the top side of the car and will support it for rotation through 360 degrees, being provided with braking means for holding the mast in any selected position to which it is rotated.

Each well 12 comprises a sleeve or housing 55 which is open at its top and closed at its bottom but is provided with a drain plug 56 in its bottom. The housing 55 is supported by means of a plate or flange 57 which is welded to the upper end thereof and which is of square outline. This plate or flange 57 rests on the horizontal portion 58 of an L-shaped supporting bracket which also includes the vertical portions 59. These portions 59 are suitably secured to the frame structure of the car or other vehicle. Braces 60 are also provided which run diagonally from the horizontal portions 58 and which are provided with horizontally disposed block portions 61 at their lower ends that are welded to the vertical portions 59 of the brackets and to the housing 55 (Figures 1 and 3). The supporting bracket portions 59 are so secured to the car frame that the housing 55 will be coaxial with the opening 62 provided in the floor 14 of the car with the flange or plate 57 engaging the lower surface to the floor around the opening. The lower end of the housing 55 is provided with a bushing 63 which is adapted to take the lateral or radial thrust of the lower end of the mast, as will later appear. This structure comprises the well 12, one of which is positioned at each corner of the car as shown in Figure 2 and remains in position therein for receiving the lower end of the mast 13.

In positioning the mast in either well 12, the lower end is merely inserted in the housing 55 with its extreme lower end disposed in the bushing 63. The lower extremity of the mast, however, will not contact with the bottom of the housing 55, since the mast 13 is supported at the upper end of the housing 55 by a roller bearing. The mast 13 is provided with a cone-shaped bearing member 64 welded thereto and resting on the angularly disposed rollers 65. These rollers 65 are carried in an outer bearing race 66 which is attached to a brake pressure plate 67. This plate 67 is provided with an integral flange 68 of square outline that overlaps the floor 14 around the opening 62 and is bolted to the flange or plate 57 beneath the floor by means of the vertical bolts 69 which pass downwardly through the opening 62. At diametrically

opposed points bolts 70 are provided which extend loosely through the plate 67 and are anchored at their lower ends to the plate 57. These bolts serve as parts of toggles for pressing the braking plate 67 downwardly and also serve to prevent rotation of this plate. Each bolt 70 has a cam member 71 on its upper end which can be rotated by means of a handle 72 mounted for transverse sliding movement therein. This cam member has a lower end so shaped that when it is rotated, it will engage the upper surface of the plate 67 with increasing pressure to cause the plate 69 to firmly engage the upper surface of the cone portion 64 of the mast. Thus, the plate 67 will be pressed downwardly at diametrically opposed points and the mast 13 will be held in any selected position to which it is rotated. When the brake is actuated the entire bearing unit including plate 67 and race 66 will be moved downwardly to prevent excessive pressure on rollers 65.

To position the mast 13 in the housing 55 it is merely necessary to insert its lower end therein and connect the bolts 68 and 70 to the plate 57. To remove the mast 13 it is merely necessary to remove the bolts 68 and 70. The bearing unit and the braking plate 67 will always be carried by the mast 13.

The swivel hook 34 may be used when the boom is to pull shoring timber stumps from the mine floor or in handling the timbers, especially preparatory to positioning in the cradle 25. For example, as shown in Figure 9, the swivel hook 34 and a cable or chain 75 may be used for lifting the timbers T from the ground, the car 11 on which the lift is mounted, or from an adjacent car 76. The car may be provided with brackets 77 supported on the upper ends of stakes 78. These brackets as shown in Figure 10 are U-shaped for receiving and supporting the timbers. The arm 17 can be used to swing the cradle 25 beneath the timber supported in brackets 77, the cradle then being rotated properly to be directly below the timber, at which time the arm 17 can be raised again to cause the timber to be cradled in the cradle 25.

The cradle 25 is removable from the upper end of the link 26 to permit the lift as a whole to be used outside the mine for general lifting or loading timbers on mine cars preparatory to entering the mine, by means of a chain or sling suspended by swivel hook 34.

It will be apparent that our device is very simple and can be removed from and repositioned on the mine car with ease. The device can handle the timbers efficiently and especially in positioning and holding them against the mine roof. The application of excessive pressure, however, to the roof will be precluded.

Having thus described our invention, what we claim is:

1. A timber lift device for use in placing timbers in a mine tunnel or the like against the roof thereof comprising a vertical mast member, a boom arm having its inner end pivoted to the mast member so that the arm member is mounted for vertical swinging movement, means for supporting the timber on the outer portion of the arm member, a fluid ram for swinging the arm upwardly to lift the timber against the roof, said ram being disposed between the mast member and the arm member and being pivotally connected to such members, a fluid pump for supplying fluid to said ram to swing the arm upwardly relative to the mast and connected to the ram by a pressure line, means for limiting the upward lifting force exerted by said ram to prevent the application of excessive forces to the mine roof by a timber carried by said supporting means on the arm member, said last-named means comprising an automatic pressure-release valve connected to the pressure line, and a manual control valve also connected to the pressure line for relieving the pressure when desired to lower the boom arm.

2. A timber lift device for use in placing timbers in a mine tunnel or the like and especially the roof thereof comprising a boom arm mounted for vertical swinging on a supporting post, means for supporting the timber transversely on the outer end of the arm, a fluid ram for swinging the arm upwardly to lift the timber against the roof, means for limiting the upward lifting force exerted by said ram, said means for supporting the timber comprising a timber-receiving cradle mounted on the outer portion of the arm for rotation through 360°, parallel linkage connected to the arm and to the cradle for keeping the cradle upright regardless of the vertical position of the arm, said parallel linkage comprising a longitudinally extending bar which is pivotally connected at its inner end to the supporting post and extends paral-

5
bel to the arm, a link pivotally connected to the outer end of said bar and to the outer end of said arm, said link extending above the arm and rotatably carrying said cradle, said link being bifurcated and the arm projecting therethrough, said bar being connected to said link by a block pivoted in said link, said bar having a threaded portion extending through said block, and an adjusting nut on said bar ahead of said block.

3. A timber lift according to claim 2 in which the projecting end of said arm has a hook swiveled thereto.

4. A timber lift according to claim 3 wherein the cradle comprises sets of prongs which receive and retain the timber, the prongs terminating below the upper surface of the timber.

5. In combination with a lift device having a vertical mast and a boom arm mounted thereon for vertical swinging movement, a supporting base having a socket for receiving the lower end of the mast, said lower end of the mast having a cone-shaped bearing portion, a roller bearing for supporting the mast in the socket, said roller bearing including angularly disposed rollers engaging said cone-shaped bearing portion, a brake at the upper end of the socket and including a plate disposed around said mast above said cone-shaped bearing portion having adjustable means for pressing it against said cone-shaped bearing portion to prevent rotation of said mast in said socket.

6. A timber lift device for use in placing timbers in a mine tunnel or the like against the roof thereof comprising a vertical mast member, a boom arm member having its inner end pivoted to the mast member so that the arm member is mounted for vertical swinging, means for supporting the timber transversely on the outer portion of the arm member and comprising a timber-receiving cradle mounted on the outer portion of the arm member for rotation through 360 degrees, a fluid ram for swinging the arm upwardly to lift the timber against the roof, said ram being disposed between the mast member and the arm member and being pivotally connected to such members, parallel linkage connected to the arm and the cradle for keeping the cradle upright regardless of the vertical position of the arm, said parallel linkage comprising a longitudinally extending bar which is pivotally connected at its inner end to the mast and extends parallel to the arm, and a link pivotally connected to the outer end of said bar and to the outer end of said arm, said link extending above the arm and rotatably carrying said cradle, a fluid pump for supplying fluid

to said ram to swing the arm upwardly relative to the mast and connected to the ram by a pressure line, and means for limiting the upward lifting force exerted by said ram to prevent the application of excessive forces to the mine roof.

7. A timber lift device according to claim 6 wherein the bar is adjustably connected to said link.

8. A timber lift device for use in placing timbers in a mine tunnel or the like against the roof thereof comprising a vehicle having a socket, a vertical mast having its lower end rotatably mounted in said socket, said socket terminating approximately at the level of the wheel axes of the vehicle, adjustable means for non-rotatably holding the mast in the socket, a boom arm member having its inner end pivoted to the mast member so that the arm member is mounted for vertical swinging, means for supporting the timber transversely on the outer portion of the arm member and comprising a timber-receiving cradle mounted on the outer portion of the arm member for rotation through 360 degrees, a fluid ram for swinging the arm upwardly to lift the timber against the roof, said ram being disposed between the mast member and the arm member and being pivotally connected to such members, parallel linkage connected to the arm and the cradle for keeping the cradle upright regardless of the vertical position of the arm, a fluid pump for supplying fluid to said ram to swing the arm upwardly relative to the mast and connected to the ram by a pressure line, and means for limiting the upward lifting force exerted by said ram to prevent the application of excessive forces to the mine roof.
